UNITED STATES PATENT OFFICE.

LARKIN STOWE, OF PLEASANT VIEW, KENTUCKY.

WATER-ELEVATING APPARATUS.

1,072,787.

Specification of Letters Patent.

Patented Sept. 9, 1913.

Application filed November 17, 1911. Serial No. 660,825.

To all whom it may concern:

Be it known that I, LARKIN STOWE, a citizen of the United States, residing at Pleasant View, in the county of Whitley and State of Kentucky, have invented a new and useful Improvement in Water-Elevating Apparatus, of which the following is a specification, reference being had to the accompanying drawing.

10 My improvement relates particularly to water elevating mechanism comprising a bucket, a windlass, and a rope, chain, or similar device, leading from the bucket to the windlass.

15 The object of the invention is to provide a cheap and durable apparatus, the operative parts of which may be readily replaced.

In the accompanying drawings, Figure 1 20 is an upright section showing my improvement applied to a well; Fig. 2 is a detail view of a pair of weights; Fig. 3 is an elevation of a bucket; Fig. 3^a is a plan of the same bucket; Fig. 4 is a detail view of 25 a yoke engaging the bail of the bucket; Fig. 5 is a side elevation of an ear on the bucket; Fig. 6 is an upright section through said ear; Fig. 7 is a plan, portions being omitted; Fig. 8 is a sectional elevation; Fig. 30 9 is a detail elevation looking toward the right in Fig. 8, the crank being omitted.

Referring to said drawings, A is the well.

B is the usual housing for containing and supporting the operating members of an 35 apparatus of the general type to which my improvement relates.

C is a hopper into which water is to be discharged from the bucket. Said hopper is supported by the housing, E.

40 D is a spout projecting outward from the outside of the housing and communicating with the hopper.

The bucket, 1, has an ordinary bail, 2, hinged to ears, 3, at opposite sides of the 45 bucket. The bucket is supported by a suspension member consisting of a wire, chain, or rope, 4, secured to the bail, 2, and passing thence upward over a guide pulley, to a windlass or drum as will be hereinafter described.

At each ear, 3, of the bucket, is a swiveled tube, 5, through each of which extends an

upright guide wire, 6. The drawings show said guide tubes, 5, secured to the ends of the bail projecting outward from the ears, 3. 55 The upper end of each such wire is suitably secured to the housing, as by means of hooks, 7, secured to the roof of the housing, B, (see Figs. 1 and 3). The lower end of each such guide wire is secured to one of two 60 weights, 8, resting upon or near the bottom of the well. Such weights are shown separated by means of a spacing tube, 9, and a binding bolt, 10, extending through said tube and said weights. Said guide wires 65 prevent said bucket from swinging laterally and also from rotating on an upright axis; but the turning of said bucket on an axis extending horizontally through the ears, 3, is permitted. To serve as a substitute for 70 or to coöperate with the swiveled tube, 5, in preventing the rotation of the bucket, a yoke, 11, having a middle slot, 12, and end apertures, 13, is applied to the guide wires, 6, and the bail, 2, the latter extending into 75 said slot from below and one of said guide wires extending through one of the apertures, 13, and the other guide wire extending through the other of said apertures. Said yoke rests by gravity on the bail. 80

For the tilting of the bucket at both limits of its travel, a weighted ear, 14, is secured rigidly to the portion of the rim of the bucket which is toward the hopper, C. Said ear is preferably formed by casting and secured by a removable bolt, 15, extending through the lower portion of said ear and the wall of the bucket, in order that the ear may be removed and applied to a new bucket when the old bucket is worn out. 90 The upper portion of said ear extends above the rim of the bucket and has an opening, 16, adapted to receive a hook, 17, secured to the hopper and projecting toward the path of the bucket and extending across the path 95 of said ear, so that when the bucket rises, said ear meets and is held by said hook, while the bucket is drawn higher and made to turn on the bail hinge and on the bearing formed between said ear and said hook, the latter entering the opening, 16. While the bucket thus turns, the water which it contains is poured into the hopper, C. When the water has been discharged the rope and

the bucket are again allowed to descend to the water. When the bucket extends to or into the water, the weight of the ear, 14, tilts the bucket sufficiently to make it dip, 5 as shown in dotted lines in Fig. 1. On drawing the rope upward, the bucket is again righted, the weight of the water and the bucket being so large relative to the weight of the ear, 14, as to practically overcome the latter and cause the bucket to 10 assume the upright position shown in Fig. 1.

The rope, 4, passes over a guide pulley, 18, in the upper portion of the housing and thence to the drum, 19, to which it is secured. 15 Said drum is loose on its shaft, 20, which rests in bearings, 21, supported by the housing. The drum and the shaft, are joined by means of a clutch. A toothed clutch member, 22, loosely surrounds the shaft, 20, and 20 is secured to one end of the drum. A shift-able clutch member, 23, is feathered around the shaft, 20, adjacent the clutch member, 22, and is engaged by a clutch fork, 24, projecting rigidly downward from the shift- 25 bar, 25, having its end slidably supported in ways, 26, in chairs, 27, supported by the housing, B.

At the opposite end of the drum, a brake consisting of a rigid brake block, 28, extends downward from the shift-bar, 25, in 30 position to bear against the adjacent end of the drum when the two clutch members are disengaged and to stand out of engagement with said drum when said clutch members 35 are engaged. As will now be readily understood, the shiftable clutch member and the brake block may be alternately engaged by shifting the shift-bar endwise first in one direction and then in the other. When the 40 clutch is disengaged, the drum is free to rotate in reverse direction in response to the down-pull of the bucket, excepting as the drum is restrained by the brake.

A shift lever, 29, is hinged by one end to a 45 support, 30, on the housing and extends thence horizontally across the shift bar and is coupled to the latter by means of a bolt, 31, extending through said shift bar and through a slot, 32, in the shift lever. To 50 prevent said bolt from binding the shift lever, a spacing tube or sleeve, 33, longer than the thickness of the shift lever surrounds said bolt.

On the drum shaft, 20, are a hand crank, 55 34, and a ratchet wheel, 35. A pawl, 36, is suitably applied to said ratchet wheel to prevent reverse rotation of said shaft.

For automatically moving the shift-bar in the direction for engaging the clutch, a contracting spring, 37, is secured by one end to 60 said bar and by the other end to one of the chairs, 27.

From the foregoing description, it will be seen that the portion of my improvement

which controls the bucket is readily applicable to any ordinary well bucket. If the guide tubes, 5, are used, they can be soldered or otherwise secured to the bail outside of each ear, 8; but these tubes may be omitted, yoke, 11, being sufficient for keeping the 65 bucket turned in proper position to engage the hook, 17, on the hopper; and said yoke receives the upper portion of the bail, with no work done on the latter, before the rope or chain, 4, is attached to the bail. The 70 weighted ear, 14, may be readily secured to the ordinary bucket by means of the bolt, 15. Hence the owner of a well having the ordinary bucket raised by a rope or chain may apply this portion of my improvement by 75 procuring the two guide wires, 6, weights, 8, yoke, 11, ear, 14, and hook, 17.

I claim as my invention:

1. In an apparatus of the nature described, the combination with a supporting structure, 85 of two upright guide members, a bucket having a bail, a yoke engaging said bail and slidably engaging said guide members, a suspension member engaging said bail above said yoke, and a rotary member in operative 90 relation with said suspension member, substantially as described.

2. In an apparatus of the nature described, the combination with a supporting structure, 95 of two upright guide members, a bucket having a bail, a yoke having a slot receiving said bail and slidably engaging said guide members, a suspension member engaging said bail above said yoke, and a rotary member in operative 100 relation with said suspension member, substantially as described.

3. In an apparatus of the nature described, the combination with a housing, of two upright guide members, a bucket, guide members swiveled to the outer ends of the bucket 105 bail and slidably engaging said upright guide members, a suspension member secured to the bail, and a rotary member in operative relation with said suspension member, substantially as described. 110

4. In an apparatus of the nature described, the combination with a supporting structure, 115 of two upright guide members, a bucket, ears on said bucket, a bail having its ends projecting outward through said ears, members swiveled to said bail ends outside of said ears and slidably engaging said upright guide members, a suspension member secured to said bail, and a rotary member in operative relation with said suspension 120 member, substantially as described.

5. In an apparatus of the nature described, the combination with a supporting structure, 125 of two upright guide members suspended from said structure, a weight applied to the lower end of each such guide member, means located between said weights for spacing the latter, a bucket in operative relation with

said guide members, a suspension member secured to said bucket, a rotary member in operative relation with said suspension member, and means for engaging and tilting

5 said bucket, substantially as described.

In testimony whereof I have signed my name, in presence of two witnesses, this first

day of November, in the year one thousand nine hundred and eleven.

LARKIN STOWE.
